UNITED STATES PATENT OFFICE.

MALCOLM W. McINTYRE, OF NEWPORT, KENTUCKY.

KNEE-REST.

1,171,450.

Specification of Letters Patent. Patented Feb. 15, 1916.

Application filed April 19, 1915. Serial No. 22,368.

To all whom it may concern:

Be it known that I, MALCOLM W. McINTYRE, a citizen of the United States, and a resident of Newport, in the county of Campbell and State of Kentucky, have invented certain new and useful Improvements in Knee-Rests, of which the following is a specification.

My invention relates to rests; and its object is to facilitate and reduce the discomfort of working in kneeling position, as in scrubbing, finishing, carpeting or similar work upon any extended flat surface, especially upon floors in buildings.

My invention consists in the combination of parts and in the details of construction and arrangement of parts as will herein be more fully described and claimed.

In the drawing: Figure 1 is a side elevation partially in section on the line $\alpha-\alpha$ of Fig. 2, and Fig. 2 is a bottom view, of a device embodying my invention.

As I prefer to construct my invention, a base or bottom 1 is composed of a board, preferably of wood, and this base has two rearward sockets 2 and two forward sockets 3, which are preferably formed by boring holes through the board. The rearward sockets 2 are located back close to the rear end of the board 1, but the forward sockets 3 are located a considerable distance back from the front of the board; in fact, being only slightly forward of the middle thereof. Each pair of sockets 2 and 3, however, are preferably alined at right angles to the length of the board; and across the top of the board, over the sockets 2 and sockets 3, are metal plates or strips 4 and 5, which are secured to the top of the board by bolts 6 and 7, respectively. Fixed to the under sides of these plates or strips 4 and 5, as by riveting, are rear casters 8 and forward casters 9, respectively, which extend down through the sockets 2 and 3, respectively.

These casters may be of any well known construction, and preferably are of the ball-bearing kind as shown, and the sockets 2 and 3 are of sufficient diameter to allow these casters to swing around freely into any position, while extending sufficiently far below the lower side of the board 1 to support the device a short distance above the floor, preferably somewhat more than half the diameter of the caster wheel.

Along the front end of the board 1 is a strip 10 extending downward, which pref-

erably is provided with a thin facing strip 11 of material adapted to make efficient frictional contact with the floor or other extended surface. Rubber is the most suitable material for this purpose. This strip 10 however, with its facing 11, does not extend down far enough to make contact with the floor or other surface when the device is supported upon all of the four casters 8 and 9.

Upon the upper side of the board or base 1 is a body of padding 12, confined by suitable material 13 which is stretched over the padding and fastened around the edge of the board, as by the tacks or nails 14, which also preferably hold a cushioning strip 15 extending continuously around the edge of the base, so that the device will not mar furniture or other objects with which it may be brought into contact. The padding 12 and material 13 may be any suitable upholstering materials, while the cushioning strip 15 is preferably of rubber.

Constructed as above described, the device will normally rest upon four casters 8 and 9.

In using the device, the person kneels upon the rear part of the device with the center of gravity of the body back of the forward casters 9, so that the device will thus maintain its bearing upon all of its four casters. The person, by pushing against the surrounding floor or other surface with the feet or hands may move the device about in any direction and thereby be transported over the surface as the work may require. However, if the person lean forward, bringing the center of gravity of the body forwardly of the forward casters 9, the front end of the device will tilt downward, raising the rear casters 8 from the floor and bringing the strip 10 and its facing 11 into frictional contact with the floor or other surface. This contact will effectively prevent further movement of the device over the surface, and will form an effective reactive means for the exertion or action of the person in operating upon the floor or other surface, as in scrubbing or finishing; and, for any kind of work which may be required to be done, will afford a firm and steady foundation for the person in doing the work. At the same time, the device is always ready, through the mere act of the person raising the body backwardly of the device, to again be supported upon

the four casters, and thus be capable of moving freely in any direction as soon as the person desires to move to a new region of the floor or other surface worked upon.

5 It will be noted that raising and lowering of the body are the natural movements of the person in doing such work; and it is not only unnecessary to use the hands or feet in any manner to effect a braking of the 10 movement of the device over the floor or surface, but, since this braking is effected by such natural movements of the body incidental to performing the work, hardly any mental effort is required. It is necessary for 15 the person to bend forward to work upon the floor or other surface, and it is a very natural act to raise the body when about to move to a new region of the floor or other surface. Therefore, the operator readily becomes 20 accustomed to the operation of the device; and while the full benefit of the cushioned rest for the knees of the person is attained, and the moving about is greatly facilitated by having a transporting means 25 rather than requiring the person to creep over the floor or other surface, there is no attendant disadvantage such as there would be incidental to the operation of some braking means which required a special effort 30 upon the part of the operator. While thus being simple in operation, the device is also simple in construction, so that it is inexpensive, both in first cost and in operation, not being liable to become deranged or to 35 require any extensive repairs.

Having fully described my invention, what I claim as new and desire to secure by Letters Patent is:

1. A knee rest comprising freely rotatable 40 transporting means and braking means operated by shifting the position of a weight supported by said rest.

2. A knee rest comprising a base, freely rotatable transporting means on the base, 45 and means on the base to engage with the surface over which the rest travels, thereby braking said transporting means.

3. A knee rest comprising a base, freely rotatable transporting means on the base, 50 and means on the base to engage with the surface over which the rest travels, thereby braking said transporting means, said means being brought into said contact by tilting said rest through different disposition of the weight thereon.

4. A knee rest comprising a base, a forward transporting means thereon, a rearward transporting means thereon, said rearward transporting means being close to the 60 rear of said base, but said forward means being a considerable distance back from the front of the base, and braking means near the front of said base adapted to make con-

tact with the floor or surface over which said rest travels when weight is imposed on 65 said knee rest forwardly of the forward transporting means, but said knee rest being adapted to bear on its forward and rear transporting means when said weight is imposed back of said forward transporting 70 means.

5. A knee rest comprising a base, rear casters on said base near its rear end, forward casters on said base a considerable distance back from its front end and only 75 slightly forward of its middle, and braking means on said base extending down therefrom near its front end, out of contact with the floor or surface when all of said casters bear on said floor or surface, but making 80 contact with said floor or surface when said main rest is tilted forward raising its rear casters from the floor or surface, and thereby preventing the movement of said main rest upon its forward casters. 85

6. A knee rest comprising a base, rear casters on said base near its rear end, forward casters on said base a considerable distance back from its front end and only 90 slightly forward of its middle, a strip extending down from said base along near its front end, and a frictional facing on said strip to make contact with the floor or surface when said main rest is tilted forward 95 raising its rear casters, and preventing movement of said main rest on its front casters.

7. A knee rest comprising a base having rear sockets near its rear end and forward sockets a considerable distance back from its 100 front end and slightly forward of its middle, said sockets being formed by holes through said base, a plate fixed to the upper side of said base and extending across said rear sockets, rearward casters mounted on 105 said plate and extending down through said sockets, a plate fixed to the upper side of said base across said forward sockets, forward casters mounted on said plate and extending down through said forward sockets, 110 said rearward and forward casters extending below the lower side of the base and forming supporting and transporting means for the knee rest, a strip fixed to said base along its front end part, and a frictional 115 facing on said strip presented downwardly and adapted to make frictional contact with the floor or other surface when said rest is tilted forward raising its rear casters, and thereby preventing movement of said rest on 120 its forward casters.
